B. MILLER

DOUBLE ACTING PLUNGER PUMP

Filed Sept. 28, 1927

UNITED STATES PATENT OFFICE.

BENJAMIN MILLER, OF LOS ANGELES, CALIFORNIA, ASSIGNOR OF ONE-HALF TO JESSE ARVEL CULP, OF VAN NUYS, CALIFORNIA.

DOUBLE-ACTING PLUNGER PUMP.

Application filed September 28, 1927. Serial No. 222,582.

This invention relates to a double acting plunger pump in which the piston cylinder of the pump is inclosed within an external casing sufficiently large to provide an annular chamber between the outside of the piston cylinder and the inner surface of said external casing, the operation of the pump being such as to alternately elevate the liquid within said annular space and within the upper portion 10 of said piston cylinder, a conduit being provided which communicates with said annular space and piston cylinder at the upper end to conduct a continuous stream of liquid from the pump.

An object of this invention is to improve upon pumps of this character with respect to compactness, simplicity of construction and economy of operation. A further object of the invention is to provide an improved 20 means for assembling and maintaining in proper relation to each other the two cylindrical casings which inclose the operating parts of the pump.

Still other objects and advantages may 25 hereinafter appear.

Referring to the accompanying drawings which illustrate a preferred embodiment of the invention, Figure 1 is a longitudinal mid-section of the working parts of the pump and 30 of the casings which inclose these parts; Figure 2 is a side elevation of the pump; Figure 3 is a cross-section on line 3-3 of Figure 1; Figure 4 is a perspective view of one of the valve elements and the guiding means carried 35 thereby.

Referring in detail to the drawings, within an external elongated casing 1 is supported a piston cylinder 2 by means of the lower closure head 4 and the upper closure head 3, 40 said heads being respectively provided with annular grooves 6 and 5 in which are seated the lower and upper ends of said piston cylinder, and lock screws 8^b which hold said lower and upper closure heads intact with 45 said casing.

At a point preferably midway between its ends, each side of said casing 1 is provided with an inlet port, consisting of a short conduit 8 which communicates with the conduit 50 chamber 7 through which the liquid has egress into the piston cylinder 2. Said conduits 8 each preferably consist of a short open-ended cap screw. These cap screws are desirably screwed into place at diametrically

opposite sides of the casing in such a way that 55 they assist in holding the external casing and the piston cylinder in proper relation to each other so that an annular chamber 9 is provided between said casing and cylinder.

In close proximity to said cap screws 8 60 are likewise positioned spacer screws 8^a which are adapted to locate the piston cylinders in alignment with the casing 1 before the cap screws 8 are screwed in position thus providing 65 a tight fit between the head of the screw 8 and the casing 1.

In addition to the port and conduit mentioned a plurality of ports 10 are provided near the upper closed end of the casing 1 and corresponding ports 11 are provided near the 70 opposite end of said casing.

The pump is provided with an operating piston rod 15 and a connecting piston rod 16. Said piston rod 16 is provided with two composite hollow piston heads 17 and 18 one near 75 each end of the piston cylinders 2. With these piston heads co-operate respectively the valve structures designated in a general way as 19 and 20. The piston heads are fixed to rod 16 and thereby maintained in spaced relation to each other as best shown in Fig. 1 of the drawings.

Referring in detail to the construction of the composite piston head 18, said head comprises a short piston sleeve 25 having at its 85 lower end a relatively thick, internally projecting flange 26, containing a plurality of ports 36, upon which is seated the expanded lower end of a helical spring 27. It is also provided with an annular lug 37^a, so as to 90 make the two piston heads 18 and 17 interchangeable. The upper end of said sleeve 25 is provided with a contracted internally threaded portion 28 within which is screwed the lower end of a connecting sleeve 29. Said 95 connecting sleeve 29 has a smooth interior surface which is slidably engaged by a plurality of upstanding guide fingers 30 that are fixed to a valve disk 31, said disk being 100 by the spring 27 yieldingly held in contact with sleeve 29, the lower end of said sleeve forming a seat for said valve disk 31.

The upper end of connecting sleeve 29 is externally screw threaded and has screwed 105 thereonto a flanged cap 35 which fits slidably within the piston cylinder 2 and forms the upper end of the composite piston head 18. Said cap is provided with a plurality of con-

tinuously open ports 36 and has also an annular lug 37 at its center into which is screwed the lower end of the connecting piston rod 16. Around the connecting sleeve 29 are provided a plurality of leather packing washers 40 separated by metallic rings 41. Each of said washers has an annular downwardly extending flap having a slidable but fluid-tight fit against the internal wall of the piston cylinder 2.

The construction of the hollow composite piston head 17 near the upper end of the piston cylinders 2 is the same as that of the piston head which has just been described and hence its parts are designated by the same reference characters. The piston head 17 is, however, arranged to force the liquid in the reverse direction with respect to the plunger cylinder 2.

Referring now to the valve construction 20, the piston cylinder 2 is formed in two sections which are united by an external coupling sleeve 45. The end portions of said coupling sleeve are internally threaded for a considerable distance and into each of these threaded portions apertured valve seats 46 are screwed down as far as possible. Each of said valve seats consists of a relatively thick disk having a central bore to receive the connecting piston rod 16 and a stuffing box 47 through which said rod plays, said stuffing boxes being directed toward each other. The central inlet conduits 8 are located between these disks 46. Upon the outer faces of these disks 46 are seated the movable valve disks 48, the latter disks being of less diameter than the internal diameter of coupling sleeve 45 but of sufficient diameter to cover the disk apertures 49. They are yieldingly held in position by a helical spring 27^a tensioned between said valve disk 46 and a spring seat 50 screwed into the external coupling sleeve 45.

Operation.

It is necessary to give the pump a few strokes in order to prime it, after which it is double acting, discharging with the down stroke as well as the up stroke.

The upper and lower composite piston heads, being connected together with a connecting rod properly spaced and working through two packing glands.

The object of the packing glands being to prevent leakage back into the well after the pump has been primed and under working pressure.

While the upper composite piston head is on the up stroke discharging its load the vacuum created below the piston head causes the upper foot valve disk to open and fill the chamber below the piston head for the next discharge.

Along with this action, the valve disk in the lower piston head is open, allowing water to pass through into the chamber below the

lower piston head, the lower foot valve disk being closed.

As soon as the upper piston head has reached top center of its stroke and starts down, the upper foot valve disk closes and the valve disk in the upper piston head opens, allowing the piston head to pass down through the liquid in the chamber held there by the upper foot valve disk in closed position.

Simultaneously with this action the lower piston head having reached its top center, the valve disk in the piston head closes. The piston head now being on the down stroke, the flaps of the packing washers being turned down, forces the liquid down through the port holes in the lower end of piston chamber and upward through the annular chamber and through another set of port holes in the upper piston chamber and out through the upper closure head.

The vacuum created above the lower piston head causes the lower foot valve disk which is above the lower piston head to open allowing liquid to enter the piston chamber and loading it for the next discharge. As soon as lower piston head has reached bottom center and starts up, the lower foot valve disk closes and the valve disk in lower piston head opens on the up stroke allowing liquid to pass through into the chamber below the lower piston head, while simultaneous with this same up stroke the upper piston head is discharging another load, and vice versa throughout the operation of the pump.

Having thus traced the action of the pump through its cycle of operation, we find a double acting discharge with a single action stroke.

In this specification and the accompanying drawings, I have described and shown a preferred form of my invention and have specifically mentioned certain of its more important objects.

I do not wish to limit myself to the forms disclosed since various changes and adaptations may be made therein without departing from the essence of my invention as herein-after claimed, and objects and advantages other than those specifically mentioned are included within its scope.

I claim:

1. In a pump, a casing having a double wall providing an annular chamber closed at both ends, the inner wall of said chamber being formed by a pair of complementary piston cylinders, united with a coupling sleeve, the opposite ends of which are contained in the ends enclosing said annular chamber, there being ports through said inner wall near each end thereof, an apertured valve seat screwed into the ends of said coupling sleeve forming a conduit chamber, means near the mid-length of said annular chamber for conducting fluid there across to

- the interior of said conduit chamber, a spring seat screwed into said coupling sleeve in spaced relation with said apertured valve seats, a valve disk to close the apertures in said valve seat, a spring to seat upon said spring seat, to oppose the opening of said valve disks, pistons within said piston cylinders, valves in said pistons, said valves co-operating with said valve disks in controlling the longitudinal flow of liquid flowing within said piston cylinders, through said ports into said annular chamber, an outlet conduit at one end of said piston cylinder and operating means for said pistons, said valves and pistons being adapted to alternately deliver fluid through said outlet conduit of said piston cylinder during the simultaneous reciprocation of said pistons.
2. In a pump, an upright external casing having a closed lower end and an inlet through its side at a distance from said closed end, a piston cylinder within said external casing and of less diameter than the latter to provide an outlet passage between said cylinder and casing, there being an inlet passage leading from said inlet port to the interior of said piston cylinder, two stationary valve structures within said piston cylinder, one of said valve structures being located above said inlet passage and the other below it, said valve structures comprising an apertured valve seat, a valve disk to seat thereupon, a spring seat in spaced relation to said apertured valve seat adapted for maintaining alignment of said piston cylinder, a tapered helical spring to seat upon said spring seat to oppose the opening of said valve disks, a lower piston head below one of said valve structures, an upper piston head above the other of said valve structures, means for reciprocating said upper piston head, and a connecting rod connecting said upper piston head with said lower piston head, said connecting rod being journaled in each apertured valve seat of above said valve structures, there being a port through the wall of the lower portion of said piston cylinder and a port through the wall of the upper portion thereof.
3. In a casing construction for pumps, an external cylindrical casing having a closure cap at each end, one of said caps having a central passage therethrough and an annular groove in its inner face around said passage and the inner face of the other closure cap having a corresponding annular groove, a piston chamber composed of complementary piston cylinders, said complementary piston cylinders each having one of their ends seated in one of said grooves, a coupling sleeve connecting the other end of said complementary piston cylinders whereby to form aforesaid piston chamber, apertured valve seats screwed into said coupling sleeve and forming a conduit chamber, a conduit communicating with said conduit chamber through which liquid has egress into said piston chamber, movable valve disks seated upon said apertured valve seats, a spring seat screwed into aforesaid coupling sleeve in spaced relation with said apertured valve disks, said spring seats abutting against the exposed ends of aforesaid complementary piston cylinders, means supported by said spring seats to yieldably hold said movable valve disks in closed position, ports contained in the walls of said piston cylinder to afford communication between them and the annular chamber surrounding the same, a piston head contained within each of said piston cylinders, operating means connecting the same, valves in said piston heads said valves co-operating with said valve disks in controlling the longitudinal flow of liquid within said piston cylinders through said ports, and through said central passage in one of aforesaid closure caps.

BENJAMIN MILLER.
